CORSET LACING CONSTRUCTION

Larkin J. Mead, Aurora, Ill., assignor to Aurora
Corset Company, Aurora, Ill., a corporation of
Illinois

Application November 29, 1935, Serial No. 52,130

1 Claim. (Cl. 2—39)

This invention relates to lacing constructions for corsets.

The main object of the invention is to provide a simple and efficient lacing construction designed to prevent scoring of the wearer's body by the lacing.

In conventional lacing constructions, the lacing extends through eyelets formed directly in the proximate, reinforced margins of two sections of the corset, and thus the lacing lies adjacent both the inner and outer surfaces of said marginal portions and close to the body of the wearer. By the use of my invention the forming of eyelets directly in the corset fabric is avoided, and the lacing does not lie beneath the inner surface of the corset sections which are connected by the lacing.

I have conceived the idea of connecting lengths of the eye-strip of hook and eye tape to each of the proximate edges of corset sections to be connected by lacings, to provide tape supported eyelets for the lacings, whereby the lacings may extend through the eyes above the tape or strip, and whereby the necessity for eyelets formed directly in the corset sections and for shields for underlying the eyelets and lacings is obviated.

In the drawing:

Fig. 1 is a fragmentary elevation of a corset showing the lacing and cooperating portions of corset sections connected by said lacing.

Fig. 2 is an enlarged section taken on the line 2—2 of Fig. 1.

In that embodiment of the invention shown in the drawing, corset sections intended to be adjustably secured together by lacings are indicated at 10, 10, the fabric of each of said sections being turned at its longitudinal edge 11. Preferably each section is provided with bones 12—12, enclosed in fabric covers 13 and 14. The fabric of a boning strip is stitched to each of the sections 10 by lines of stitching 15 and 16. To provide eyes for the lacings, I preferably use the eye strip of hook and eye tape. The type of eye strip which I prefer to use for this purpose comprises a strip of fabric 17, folded upon itself at 18, 19 and 20. An insert strip 21 of rubberized material or other springy material is placed between two laps of the fabric 17 formed by the fold 18. Eyes 22 are secured to that part of the strip comprising

the fabric 17 and insert 21 by stitches 22'. The eyes are located inwardly of the edge 18 of the fabric 17 of the eye strip. The eye strip with the folded edge 20 covering the inner ends of the eyes 22 is placed beneath the turned edge 11 of the fabric 10 of the corset so that said edges 11 and 20 register and then the fabric 10 and the eye strip are connected by lines of stitching 23 and 24, and all the parts including the fabric 10, eye strip 17 and boning covers 13, 14 are connected 10 by stitching 25. The lacing is indicated at 26.

The parts are readily assembled, economical in construction and efficient for their intended purposes. The lacings, being disposed above the fabric 17 of the eye strip, and cushioned thereby, do 15 not score the body of the wearer.

Changes may be made in details of construction without departing from the scope of my invention and I do not intend to be limited to the exact form shown and described, except as set forth 20 in the appended claim. For example, the eyes 22 may be secured to the supporting strip either by stitching, riveting or other means.

I claim:—

A corset lacing construction comprising a pair 25 of corset body sections to be connected together, the fabric of each body section having an turned inwardly, with the lower of its folded edges protruding beyond the upper folded edge and eyes secured to said folded fabric between the upper and lower folds, each eye-carrying strip having its upper folded edge beneath and flush with the turned inward edge of a body member, a row of stitches 30 adjacent the turned edge of the body member securing the underlying eye-carrying strip to said body with part of the eyes and the lower folded edge of the eye-carrying strip projecting beyond the body member, a fabric covered stiffening strip 35 for each body member, a line of stitches connecting one edge of the stiffening strip directly to the under side of the corset body, a line of stitches connecting the other edge of the stiffening strip to the under side of the eye-carrying strip and the body member, and lacing connecting the eyes 40 of the two body members.

LARKIN J. MEAD.
